UNITED STATES PATENT OFFICE.

HARRY L. STALEY, OF CHARLEROI, PENNSYLVANIA.

ENVELOP.

No. 902,341.

Specification of Letters Patent.

Patented Oct. 27, 1908.

Application filed February 6, 1907. Serial No. 356,059.

To all whom it may concern:

Be it known that I, HARRY L. STALEY, a citizen of the United States of America, residing at Charleroi, in the county of Washington and State of Pennsylvania, have invented certain new and useful Improvements in Envelops, of which the following is a specification, reference being had therein to the accompanying drawing.

10 This invention relates to envelops, and the invention has for its object to provide a simple and inexpensive envelop, that cannot be surreptitiously opened without detection. To this end, I have devised an envelop made 15 from a single piece of paper, or similar material, the envelop being provided with sealing flaps or tongues adapted to interlock with the folded flaps of the envelop, whereby said flaps cannot be opened without injuring the 20 sealing flaps or tongues.

The details of the construction entering into my invention will be hereinafter more fully described and then specifically pointed out in the appended claims, and referring to 25 the drawing forming part of this application, like numerals of reference designate corresponding parts throughout the several views, in which:—

Figure 1 is a developed view of my improved envelop, Fig. 2 is a plan of the envelop folded and sealed, Fig. 3 is a longitudinal sectional view of the same, Fig. 4 is a plan of a portion of the envelop illustrating the sealing tongue provided with adhesive material, Fig. 5 is a plan of the envelop folded and sealed by adhesive material, Fig. 6 is a longitudinal sectional view of the same, Fig. 7 is a plan of a portion of the envelop illustrating one of the tongues thereof adapted 35 to be sealed with wax or similar material, Fig. 8 is a plan of a folded envelop as sealed by wax, and Fig. 9 is a longitudinal sectional view of the same.

To put my invention into practice, I construct my improved envelop of a piece of paper, paperoid or other suitable material, the envelop consisting of a body portion 1 having side flaps 2 and 3, said flaps being approximately the same size as the body portion 1 of the envelop. The flaps 2 and 3 are provided with a plurality of slits or slots 4, 5 and 6, disposed at right angles to the tongues 7 and 8 the object of which will be presently described.

55 The ends of the body portion 1 are provided with tongues 7 and 8, the tongue 8 be-

ing preferably slightly longer than the tongue 7. In Figs. 2 and 3 of the drawing, I have illustrated the envelop as folded and sealed, and to accomplish the same, the flaps 2 and 3 are folded inwardly upon the dotted lines 9 and then the tongues 7 and 8 are folded inwardly upon the dotted lines 10. The tongue 7 is inserted in the registering slits or slots 4 and passed outwardly through the 65 slits or slots 5, the end of the tongue 7 lying centrally upon the flaps 2 and 3, as designated at 11. The tongue 8 is then passed through the registering slots 6 and out through the registering slots 5, and then is 70 inserted in the slots 5 on top of the tongue 7. The tongues 7 and 8, flaps 2 and 3, and the body of the envelop and its contents may then be stitched together by a thread, cord or wire as at 12, thus firmly locking the contents 75 within the envelop and preventing the tongues or flaps from being opened without marring or injuring the envelop.

In Figs. 4 to 6 inclusive, I have illustrated the tongues 7 and 8 as being provided with adhesive material 14, the envelop being folded as just described, and the tongue 7 adhesively secured to the envelop, and the tongue 8 adhesively secured to the tongue 7 between the slits or slots 4 and 5.

A still further manner of sealing the envelop is illustrated in Figs. 7 to 9 inclusive, wherein I have provided the tongue 8 with an opening 15, and after the envelop has been folded and the tongues positioned as heretofore described, sealing wax or a similar material 16 is placed upon the tongue 8 over the opening 15, the sealing wax being adapted to pass through said opening and adhere to the tongue 7.

To insure a perfect closure of the envelop and prevent the same from being surreptitiously opened, I preferably stitch the same, the stitches being removed when it is desired to open the envelop.

Such changes in the size, proportion and minor details of construction, as are permissible by the appended claims, may be resorted to without departing from the spirit and scope of the invention.

What I claim and desire to secure by Letters Patent, is:—

An envelop consisting of a body having side flaps extending from the longitudinal edges thereof and having tongues of reduced width projecting from the ends of the body, said tongues being of unequal length, each of

2
said side flaps corresponding substantially in size with the body and each provided with a plurality of slits spaced apart at right angles to the body, the said side flaps adapted to be 5 folded over onto said body and said tongues being each passed through a plurality of the slits in the side flaps with the longer of the tongues also passed through one of the slits occupied by the shorter of said tongues, and

means extending through the tongues, the 10 side flaps and the body for securing the parts against opening without destroying the same.

In testimony whereof I affix my signature in the presence of two witnesses.

HARRY L. STALEY.
